(57) **CLAIM**

The ornamental design for a set of decorative elements for a watch bracelet, as shown and described.

DESCRIPTION

FIG. 1 is a front plan view of a set of decorative elements for a watch bracelet showing my new design;

FIG. 2 is a back plan view thereof;

FIG. 3 is a top elevational view thereof;

FIG. 4 is a bottom elevational view thereof;

FIG. 5 is a right side elevational view thereof;

FIG. 6 is a left side elevational view thereof;

FIG. 7 is a front, bottom perspective view thereof;

FIG. 8 is a back, bottom perspective view thereof; and,

FIG. 9 is an enlarged perspective view of one of the set of decorative elements for a watch bracelet shown for completeness of illustration.

The broken lines shown in the drawings illustrate environmental subject matter and form no part of the claimed design.

1 Claim, 8 Drawing Sheets
